UNITED STATES PATENT OFFICE.

WILLIAM F. DIDEN, OF MILTON, FLORIDA.

REVERSING-GEAR.

SPECIFICATION forming part of Letters Patent No. 393,219, dated November 20, 1888.

Application filed June 21, 1888. Serial No. 277,821. (No model.)

To all whom it may concern:

Be it known that I, WILLIAM F. DIDEN, a citizen of the United States, residing at Milton, in the county of Santa Rosa and State of Florida, 5 have invented certain new and useful Improvements in Reversing-Gear for Steam-Engines; and I do hereby declare that the following is a full, clear, and exact description of the same, reference being had to the annexed drawings, 10 making a part of this specification, and to the letters and figures of reference marked thereon.

Figure 1 of the drawings is a front elevation of my improved reversing-gear, showing it in 15 an adjusted position in dotted lines; Fig. 2, a top plan view; Fig. 3, a side elevation, partly in section; and Fig. 4, a detail view showing the slotted plates through which the ends of the arms on the shifting device project.

20 The present invention has relation to that class of reversing valve-gear for steam-engines wherein the usual link for this purpose is dispensed with, and the object of the invention is to provide a more cheap, simple, easily-operating, and effective means whereby the motion of the steam-engine may be quickly and effectively reversed, in order that the engine-shaft may be made to revolve forward or backward at the will of the engineer.

25 The invention consists in the several details of construction, substantially as shown in the drawings, and hereinafter described and claimed.

In the accompanying drawings, A represents 30 the usual disk, which may be provided with braces at the back to increase its strength, as shown at *a*, and has radial slots *b* diametrically opposite each other, through which project the toothed sectors *B*, hereinafter 35 described. Upon the outer face of the disk *A* are grooves *c* to form guides for tongues *d* upon the inner face of segmental plates *C*, said plates being connected to the disk *A* by means of screws *e*, which pass through the plates and 40 through slots *f* in the disk, as shown in dotted lines, Fig. 1.

The inner edges of the segmental plates *C* are inclined, as shown at *g*, Fig. 3, so that when the plates are in position on the disk a 45 dovetail space will be formed between them to receive a correspondingly-dovetailed rack-bar, *D*, thereby retaining it in a true diametrical

line when in motion, and also more effectually forming a guide for the bar, as well as preventing it from working loose. To compensate 55 for any frictional wear of the edges of the segmental plates and the rack-bar, the plates are rendered adjustable by the means hereinbefore stated, which is accomplished in the following manner—viz., by loosening the set-screws *e*, 60 when the slots through which the screws pass will admit of the plates being moved nearer to each other, after which the nuts *h* are tightened on the ends of the screws, which will firmly hold the plates in position on the disk. 65 To prevent any lateral displacement of the plates *C* and forcing them to move in a straight line when being adjusted, the grooves *c* and tongues *d* are provided, which have been hereinbefore referred to.

The rack-bar *D* is provided with a hub, *i*, to receive the collar *j* of the arm *E*, to which the valve *F* is connected, and said hub has an elongated opening, *k*, through which extends 70 the shaft *l* of the disk.

The back or inner side of the disk *A* is formed with a flat-sided hub, *m*; or, if preferred, it may be circular or other shape, as found most desirable, and upon this hub slides 75 the disk *G*.

The toothed sectors *B* are suitably pivoted to the flanges *H*, cast on the back of the disk *A*. Although any well-known means may be employed to connect the sectors to the flanges, so that any frictional wear may be taken up 80 when the sectors become loose, I prefer to employ the tapering screws *n* and nuts *o*, and, if desired, boxes may be used fitted in the holes of the flanges *H* to receive the screws. The hub *m* may also be changed from the form 85 shown and made cylindrical, with feathers to receive the disk *G* and prevent it turning thereon. These changes, coming within ordinary mechanical skill and being obvious to the ordinary mechanic, I reserve the right to make 90 such changes without departing from the principle of my invention.

The toothed sectors *B* are connected to the sliding disk *G* by means of links *p* pivoted thereto and to arms *r* projecting from the hub 100 *s* of the disk *G*. The disk *G* is caused to slide back and forth on the hub *m* by means that will now be described. The disk *G* has a groove around its periphery, in which fits a

band or yoke, I, which is suitably provided with arms K, extending through vertically-inclined slots *t* in the sides L of a vertically-movable plate, M, and also through horizontal slots *u* in the stationary plates N. To the vertically-movable plate M is connected the bell-crank lever O by means of a link, v, said lever engaging with one of two notches in a segmental bar, P; or any other preferred 10 and well-known means may be employed for holding the lever in its position when the valve is reversed.

I desire it to be understood that any well-known means may be employed for operating 15 the plate M, and therefore I do not desire to confine myself to that shown, as it is evident that the non-essential features of the device that come within the judgment of ordinary mechanical skill may be variously modified 20 and changed and still come within the scope of my invention. When the lever O is brought to the position shown in dotted lines, Fig. 1, the plate M will be raised, and by means of the inclined slots in the sides L of the plate 25 the disk G will be carried forward through the medium of the arms K, which enter the slots, the inclined slots acting as cams on the arms. When the disk is forced forward by means of the link-connection with the sectors 30 B, the teeth thereof will be brought in engagement with the rack-bar D, and by means of said bar the valve-gear is reversed, as shown in dotted lines, Fig. 1.

Having now fully described my invention, what I claim as new, and desire to secure by 35 Letters Patent, is—

1. The disk A and movable rack-bar D, in combination with the toothed sectors B, pivoted on the disk, and the sliding disk G, connected with the sectors by means of suitable 40 links, substantially as and for the purpose set forth.

2. The combination, with the disk A and toothed sectors B, of the adjustable segmental plates C and the rack-bar D, located between 45 the plates, substantially as and for the purpose described.

3. The combination, with the toothed sectors B and disk A, having grooves *c* on its face, of the rack-bar D and adjustable segmental 50 plates C, having tongues *d* upon their inner faces, substantially as and for the purpose set forth.

4. The combination, with the sliding disk G, toothed sectors B, and disk A, of the dovetail 55 rack-bar D and the adjustable segmental plates C, having inclined edges *g*, substantially as and for the purpose specified.

In testimony that I claim the above I have hereunto subscribed my name in the presence 60 of two witnesses.

WILLIAM F. DIDEN.
